UNITED STATES PATENT OFFICE

2,436,044

ARTICLE HOLDER

Bruno J. Hudash, Chicago, Ill.

Application March 10, 1944, Serial No. 525,917

4 Claims. (Cl. 65—65)

1

This invention relates to a novel article holder adapted for placement upon a table for containing cylindrical articles, knives, forks, spoons and napkins or other table utensils and concerns itself with a structure susceptible of being stamped from sheet metal and easily assembled to produce a compact and durable holder of pleasing symmetry.

The invention comprises the novel structure and combination of parts hereinafter described and more particularly pointed out and defined in the appended claims.

In the accompanying drawing which illustrates a preferred form of this invention and in which similar reference characters refer to similar features in the different views:

Fig. 1 is a front elevational view of an article holder involving this invention.

Fig. 2 is a top plan view of the same

Fig. 2 is a top plan view of the same.
Fig. 3 is a rear elevational view of the holder, and

Fig. 4 is a sectional view taken substantially upon the line 4—4 of Fig. 1 looking in the direction of the arrows.

In referring now to the drawing which illustrates the preferred embodiment of this invention, there is shown an article holder comprising a semi-cylindrical base 6 which may be stamped from sheet metal to provide an elevated platform 5a and a downwardly extending flange 5b having a forwardly extending foot 5c on the arcuate perimeter. This foot may be reinforced by doubling or folding the metal as shown in Fig. 4.

Fig. 4. A channel-like and oblong member 6 consisting of side walls 7 and 8 and end walls 9 which also may be made from sheet metal is attached to the rear margin of the platform 5a by welding or the like. Partitions 10 divide the channel-like member into a plurality of separate compartments for containing table utensils such as knives, spoons and forks.

Upon the front wall of the upright member 6, there are attached a plurality of band-like keepers 11, 12 and 13 adapted for containing cylindrical articles such as salt and pepper shakers and vinegar jars. The ends of these keeper bands are welded or soldered to the wall 7 while the lower edges may be similarly attached to the top of the platform 5. These keepers may be made of any suitable size and of different sizes.

Toothpick holders 14 shown as of cylindrical form and preferably made of sheet metal are attached in the corners between the walls of the keepers 11 and 13 and the wall 1. These holders

are attached to the wall 7 and to the outer surfaces of the keepers 11 and 13 and their lower edges are attached to the platform preferably by welding or soldering. They not only serve as holders, they close the objectionable corners and also serve to laterally brace the keepers therebetween.

Upon the rear wall 8 of the member 6, there is yieldingly attached a keeper plate 15 to the ends of which coil springs 16 are secured which in turn are anchored to the wall 8 under sufficient tension to properly support the plate 15. Napkins are adapted to be retained between the wall 8 and plate 15.

15. It will be appreciated that the construction in which the keepers 11, 12 and 13 are attached to both the upright member 6 and the base 5 is well braced. The keepers serve to laterally brace the upright article holding member 6 and this 20 would preclude the upright member from listing in either direction thru its minor axis. Likewise, the keepers serve to brace each other in lateral directions. As a result, a very durable structure is obtained.

25 It will further be appreciated that in stamping the parts from sheet metal and assembling the same in the manner stated, much time and labor can be saved in the manufacture. Yet the device may be made from plastics.

vice may be made from plastics.

30 It is possible to easily handle and transport the holder from the table to the kitchen to receive the utensils after they are washed and dried and then if desired it may be placed in a closet or cabinet until it is desired to use the

35 same again. In this manner, the device becomes very useful.

I am aware that many changes may be made and various details of construction varied without departing from the principles of this invention so I do not propose limiting the patent granted otherwise than necessitated by the prior art and appended claims.

I claim as my invention:

45 1. In a device of the class described, a flat base having a rear straight edge and a front arcuate edge, an upright channel-like article holding member having a front wall and a rear wall in parallel relation, said walls having their bottom edges resting upon and secured to said base with the rear wall in flush relation with the rear edge, a series of article holding keepers having lateral edges attached to the front wall of said member and having lower edges attached to said base and serving to brace said member.

55 2. In a device of the class described, a base

having a straight rear edge and a front arcuate edge, an upright article holding member having a rear wall and a front wall in parallel relation welded to said base, a series of article holding keepers having lateral edges secured to the front wall of said member and lower edges supported upon said base and serving to brace said member.

3. In a device of the class described, a flat base having a rear straight edge and a front arcuate edge, an upright channel-like article holding member having a rear wall substantially flush with said straight edge and a front wall in parallel relation to the rear wall, said walls having their bottom edges resting upon and secured to said base and a series of parti-cylindrical article holding keepers having lateral edges attached to said front wall and having lower edges supported upon said base and serving to brace said channel-like member.

4. In a device of the class described, a flat base having a rear edge and a front arcuate edge, an upright channel-like article holding member having a front wall and a rear wall in parallel relation, said walls having the lower edges resting upon and secured to said base with the rear wall in substantially flush relation with the rear edge, a series of article holding keepers having lateral edges attached to the front wall of said member and having lower edges resting upon said base and serving to brace said member.

BRUNO J. HUDASH.
